UNITED STATES PATENT OFFICE

HARRY M. ZELTNER, OF CINCINNATI, OHIO, ASSIGNOR TO THE BALDWIN COMPANY,
OF CINCINNATI, OHIO

DESIGN FOR A RADIOCABINET

Application filed April 18, 1929. Serial No. 30,928. Term of patent 3½ years.

To all whom it may concern:

Be it known that I, HARRY M. ZELTNER, a citizen of the United States, residing at Cincinnati, in the county of Hamilton and State of Ohio, have invented a new, original, and ornamental Design for Radiocabinet, of which the following is a specification, reference being had to the accompanying drawing, forming part thereof.

Figure 1 is a side view and Figure 2 is a front view of a radio cabinet, showing my new design.

I claim:

The ornamental design for a radiocabinet as shown.

HARRY M. ZELTNER.
